UNITED STATES PATENT OFFICE.

EDWARD SAMUEL WARREN, OF SAN FRANCISCO, CALIFORNIA.

EXCHANGE-RECEPTACLE FOR MERCHANDISE.

1,297,761.

Specification of Letters Patent. Patented Mar. 18, 1919.

Application filed October 29, 1917. Serial No. 198,910.

To all whom it may concern:

Be it known that I, EDWARD SAMUEL WARREN, a citizen of the United States, residing at the city and county of San Francisco and State of California, have invented new and useful Improvements in Exchange-Receptacles for Merchandise, of which the following is a specification.

This invention relates to receptacles for exchanging packages of merchandise, and more particularly bottled goods. The device is especially intended for the exchange of empty milk bottles for filled ones, being adapted to be placed out of doors of homes for receiving filled bottles of milk delivered by a tradesman in exchange for empty bottles which are required to be returned by the household.

Custom in these matters has established an exchange system whereby the tradesman as he delivers one or more bottles of milk to a home on one day collects at the same time the empty bottles resulting from the previous day's supply. In practice, the householder frequently forgets to place the empty bottles where they can be conveniently collected by the tradesman with the result that they accumulate in such numbers as to tax the supply of bottles kept on hand by the tradesman and are also liable to become broken or lost. Even when the householder does remember to return the empty bottles he places them out of doors several hours previous to the tradesman's coming with the danger of their being stolen.

The object of the present invention is to provide a receptacle for both empty and filled bottles whereby it becomes necessary for the householder to place an empty bottle therein before the filled bottle can be removed, and similarly before the tradesman or others can remove an empty bottle it is necessary to first deposit a filled bottle therein.

One form which my invention may assume is exemplified in the following description and illustrated in the accompanying drawings, in which—

The figure shows a vertical central sectional view of a device embodying my invention.

The device herein shown and described in its present form comprises a cabinet 10 hav-

ing a partition 11 dividing it into two compartments A and B, each closed by means of a vertically sliding door 12 opening downward by gravity, the doors being preferably arranged at opposite sides of the cabinet. The cabinet is adapted to be suspended from nails or hooks on a wall or other support.

Within each compartment is a depressible member 13, shown in the form of a pedestal, upon which a bottle is placed, each pedestal being arranged upon a stem 14 extending through the bottom of the cabinet and slideable vertically therein. At the lower end of each stem is a lever 15 fulcrumed on a support 16 centrally of the cabinet and extending to the opposite side where it connects through a link 17 with a bell crank lever 18. On the outer end of the bell crank lever is formed a hook 19 for coöperation with a lug 20 on the adjacent sliding door. The connections are such that when the pedestal is depressed by the weight thereon the bell crank lever has its hook projecting out of the path of the lug.

Adjacent each door and at the bottom of the cabinet is a pivoted latch 21 for coöperation with a second lug 22 on the door and this latch is normally projected into the path of its lug by means of a weighted lever 23 extending across to the opposite sides where its end lies in the path of a projection 24 on the adjacent door. These levers are pivotally mounted on pins 26 held by brackets 27 extending downwardly from the bottom of the cabinet and in parallel relation to each other, the outer end of the levers being fitted with pivoted links 28 which connect them with the latch members 21. When one of the doors is closed the projection 24 thereon lifts the coöperating lever 23 and thereby moves the connecting latch 21 into inoperative position. The door whose latch 21 has thus been released, assuming its hook 19 has also been released by reason of the bottle having been previously placed in the opposite compartment, will thereupon fall to open position. In so doing it allows its coöoperating lever 23 to lower and retain the connecting latch 21 in operative position.

In operation and assuming the parts are in the position shown in the drawing, which

is the condition after the tradesman has deposited a filled bottle in compartment A and closed the door thereof, it will be seen that the door of the latter compartment is locked 5 both by the hook 19 and latch 21. A mere closing of the door of compartment B will have the effect of releasing only the latch 21 of the opposite door. To succeed in unlocking the closed door it is necessary that 10 an empty bottle, as shown in dotted lines, be placed on the pedestal in compartment B in order that its weight may act to release the hook 19 on the door of the opposite compartment. Therefore, two things are necessary to open a closed and locked door, 15 namely, the presence of a weight on the pedestal within the opposite compartment and the closing of the door of the latter.

To insure that the weight in the case of 20 compartment B shall be an empty bottle, I arrange a cone-shaped boss 25 upon the pedestal over which the open mouth of the inverted bottle fits. Any other form of weight will not remain in place on the pedestal.

25 When the empty bottle has been put in place in compartment B and the door closed, the door of compartment A instantly opens and allows the latch 21 on the right-hand side to move into engagement with the lug 30 22 on the door of compartment B. The full bottle in compartment A is then removed by the householder. The door of compartment B is now closed and locked and cannot be opened to gain access to the empty 35 bottle until a full bottle is placed in compartment A and the door of the latter closed. The locking mechanism is preferably located entirely beneath the cabinet and inclosed by a false bottom C.

40 The foregoing described mechanism not only insures security of the filled and empty bottles from theft and protection of the same from contamination and the elements, but is also an absolute check upon the exchange of empty bottles for filled ones, and vice versa, making it necessary for the householder to deposit an empty bottle in the receptacle before obtaining a filled one and likewise for the tradesman to deposit a filled 50 bottle before getting the empty one.

Various changes in the construction and arrangement of the several parts herein shown and described may be employed without departing from the spirit of my invention as disclosed in the appended claims.

Having thus described my invention what I claim and desire to secure by Letters Patent is:

1. An exchange receptacle for packages 60 comprising duplex compartments, a door in each of said compartments, a pair of latch devices for each of the doors, means in each compartment requiring the presence of a package to release one of the latches of the

other compartment, and means effected by 65 the movement of the door of the other compartment to release the second latch device of the filled compartment.

2. An exchange receptacle for packages 70 comprising duplex compartments, a door for each compartment, separately operated latch devices for each of the doors, means requiring the presence of a package in one of the compartments to release one of the latches of the other compartment, and means requiring the closing of the door of the other compartment to release the second latch of the compartment within which the package is contained.

3. An exchange receptacle for packages of 80 merchandise comprising duplex compartments, a door in each, a latch device for each of the doors, means in each of the compartments upon which a package of merchandise is placed and operative by the weight 85 thereof to release the latch on the door of the opposite compartment and an auxiliary latch device for each of the doors normally in operative position but released by the movement of the opposite door to closed 90 position.

4. An exchange receptacle for packages of merchandise comprising duplex compartments, a door in each, a latch device for each of the doors, a depressible member in each compartment adapted to receive a package, connections between each depressible member and the latch device on the door of the opposite compartment operative to move the connected latch device to ineffective position when the member is depressed and an auxiliary latch device for each door normally in operative position and controlling means therefor comprising a weighted lever projecting into the path of the opposite door and raised thereby when such door is in closed position to release its connected latch.

5. An exchange receptacle for packages of merchandise comprising a cabinet divided into separate compartments, a vertically 100 slideable door in each compartment opening downwardly by gravity, a depressible member in each compartment adapted to receive a package of merchandise, a latch for each door moved to inoperative position by depression of the member in the opposite compartment and an auxiliary latch for each door normally in operative position and released by movement of the opposite door to closed position.

6. An exchange receptacle for packages comprising duplicate inclosing compartments, a door upon each compartment and by which the package is concealed, latch 125 means for holding the doors in their closed position, gravity operating means whereby the presence of a package in one compartment will release the door in the opposite

compartment and the absence of a package in said opposite compartment will cause the locking of the door in the first-named compartment, and complementary releasing means actuated by the closing of one of the doors to complete the release of the other of said doors.

In testimony whereof I have hereunto set my hand in the presence of two subscribing witnesses.

EDWARD SAMUEL WARREN.
